US00D542940S

(12) **United States Design Patent** (10) Patent No.: **US D542,940 S**
(45) Date of Patent: **** May 15, 2007**

(54) **PROFILED COVER FOR BRIDGING A GAP
BETWEEN FLOOR COVERINGS OF
DIFFERENT HEIGHTS**

(76) Inventor: **Franz Neuhofer, Jr.**, Haslau 56,
A-4893 Zell am Moos (AT)

(**) Term: **14 Years**

(21) Appl. No.: **29/234,280**

(22) Filed: **Jul. 15, 2005**

(51) LOC (8) Cl. **25-01**

(52) U.S. Cl. **D25/136; D25/135**

(58) Field of Classification Search 52/211,
52/212, 213, 416, 417, 419, 420, 459, 461,
52/464, 465, 468, 469, 470, 471, 290, 287.1;
49/411, 467; D25/60, 61, 136, 164, 135
